BOX LID PRESSING AND NAILING MACHINE

Gerald C. Paxton, Harry D. Benson, and Charles H. Johnson, Santa Ana, Calif., assignors, by mesne assignments, to Food Machinery Corporation, a corporation of Delaware

Application September 24, 1935, Serial No. 41,896

8 Claims. (Cl. 1-10)

Our invention relates to the packing of fresh fruits and vegetables for shipment and has particular reference to a novel form of flusher for use on box lidding machines. Fruits and vegetables are usually packed in boxes or similar containers with the upper portion of the pack disposed above and in overlying relation with the upper edges of the sides and ends of the box, forming what is commonly known as a "crown pack". The overfilled boxes are conveyed from the packing tables to lidding machines where lids are arched over the pack and nailed at their ends to the box ends. The arched lids, in tending to straighten out, exert a constant pressure on the produce thus resulting in a tight pack if the latter shrinks during shipment.

In order to bring the lid ends into contact with the box ends, the crown portion of the pack must be partially pressed into the box, and suitable means must be provided on the lidding machine to engage the fruit overlying the upper edges of the box and move this fruit inward from over the box edges to prevent injury thereto by the box edges during the pressing operation. In lidding machines commonly used for lidding boxes of fruit the means for accomplishing this function along the sides of the box usually operate as "flushers". The members for accomplishing this function at the ends of the box normally extend between the ends of the box and the lid while performing their function and are therefore known as "tuckers". Where the terms "flusher" and "tucker" are used in the claims, however, it is not desired that these terms be given a more restricted interpretation than necessary to distinguish the invention from the prior art.

In the packing of fruits and vegetables, the containers are usually of standard width and length but often of two different heights, the high boxes being known as "standard" and the low boxes as "half boxes".

In certain box lidding machines, such as disclosed in the copending application of Hale Paxton et al., Serial No. 688,104, filed September 5, 1933, now Patent No. 2,084,048, dated June 15, 1937, for Automatic lid nailing and strapping machine, the flushers are carried by the box supporting table and are designed for use on boxes of substantially uniform height.

An object of our invention is to provide a box lidding machine having flushers on the table thereof in which the flushers are movable vertically in relation to the box supporting table to permit the flushers to engage the crown portion 55 of the pack of boxes of different heights.

Another object of our invention is to provide flushers on the box supporting table of a lidding machine that are automatically positioned in vertical relation to said table in response to vertical movement of table. 5

In addition to the aforementioned "standard" and "half boxes" employed for shipment of fruits and vegetables, "domestic" and "export" boxes are used, the latter having thicker shooks than the former. 10

A further object of our invention is to provide flushers for a box lidding machine that are readily adjustable for operation on either domestic or export containers.

Further objects and advantages will be made manifest in the following description taken in connection with the accompanying drawings, in which:

Fig. 1 is a fragmentary front elevational view of a preferred form of lidding machine of my invention. 20

Fig. 2 is a side elevational view looking in the direction of the arrow 2 of Fig. 1 and showing a full-height box on the table, with the latter lowered and with the flusher mechanism set to operate on this box. 25

Figure 3 is a fragmentary view similar to Figure 2 and illustrating the table raised sufficiently to cause actuation of the side flushers of the invention. 30

Figure 4 is a view similar to Figure 2 with a half-height box on the table with the latter in its lowermost position and with the flusher mechanism set for operating on this kind of box. 35

Figure 5 is a view similar to Figure 4 with the table raised sufficiently to cause the side flushers to be actuated.

Fig. 6 is a detail perspective view of a portion of one of the side flushers of the machine of my invention. 40

Fig. 7 is a fragmentary, vertical sectional view taken on the line 7-7 of Fig. 1, showing the operation of the machine in relation to a domestic fruit box.

Fig. 8 is a view similar to Fig. 7, showing the operation of the machine in relation to an export box, and

Fig. 9 is a fragmentary, detail view looking in the direction of the arrow 9 of Fig. 6.

Referring specifically to the drawings, a pack pressing and lid securing machine 10, comprising a preferred embodiment of my invention is shown in Fig. 1, this machine including a frame 11, a power unit 12, a box supporting table 13, and nailing mechanism 14. 50

The frame 11 includes a base (not shown) from which front and rear corner posts 18 and 19 respectively extend. Connected to the upper ends of the posts 18 and 19 are horizontal plates 20 and 21 respectively.

The power unit 12 includes a motor 25 controlled by a switch 26. The motor 25 causes the table 13 to be raised or lowered at the will of the operator as clearly described in the above referred to copending application.

The box supporting table 13 includes identical end plates 30, one of which is shown in Fig. 2. Each of the plates 30 is formed to provide a pair of vertical slots 32. Pivotedly mounted on each 15 of the plates 30 are levers 34 and 35, these being connected by a tie rod 36, the levers 34 and 35 being normally urged to the position in which they are shown in Fig. 2 by an extension spring 37 extending from the lever 35 to the tie rod 36, 20 a stop pin 38 being provided on the lever 35 for engagement with the tie rod 36 to limit the outward movement of the levers 34 and 35. Secured at their ends to the plates 30 are pairs of bars 40 between which rollers 41 are rotatably mounted as shown in Fig. 7. Provided on the table 13, 25 as shown in Fig. 1, are suitable stops 42 and 43 for positioning a box longitudinally on the table 13.

Pivotedly mounted on the table 13 are front 30 and rear side flushers 45 and 46 respectively, each of these including a shaft 47 received at its ends in the slots 32 of the plates 30. Fixed on opposite ends of each of the shafts 47 are arms 48 having rollers 49 on their upper ends, the rollers 49 normally resting in suitable blocks 50 fixed on the corner posts 18 and 19 as shown in Fig. 2. Connected to the lower extremities of the arms 48 are extension springs 51, the latter tending to urge the flushers 45 and 46 outward as shown in 35 Fig. 2. Fixed on the corner posts 18 and 19 in alignment with the rollers 49 are cam bars 52. Welded, or otherwise secured to the shafts 47 (Fig. 6) of the flushers 45 and 46 are upstanding bars 55 having flusher bars 56 secured to the 40 upper ends thereof.

Mounted on each of the bars 55 is an apertured block 58, each pair of the blocks 58 carrying a pin 59 upon which a U-shaped stop 60 is pivotedly mounted. The U-shaped stop 60 on the 45 right hand side of the front flusher 45 is formed as shown in Fig. 6 to provide a lever 62. Extending from a suitable pin 63 on the lever 62 to the adjacent bar 55 is an overthrow extension spring 64, the purpose of which will be described herein-after.

Pivotedly mounted on each of the shafts 47 below the U-shaped stops 60 are bell cranks 66, the cranks 66 on each of the shafts 47 being rigidly connected by bars 67 as shown in Figs. 1 50 and 6. The outward extending arm of each of the bell cranks 66 is connected to the U-shaped stop 60 thereabove by a link 69, while the downward extending arms of the front cranks 66 are connected to similar arms of the rear cranks 66 by horizontal links 70 as shown in Figs. 7 and 8. Provision of the bell cranks 66 and links 69 and 55 70 cause all of the stops 60 to operate simultaneously in response to manual operation of the lever 62.

The aforescribed levers 34 and 35 are actuated by a control mechanism 72 which includes a shaft 73 journalled in bearings 74 on the posts 18 as shown in Fig. 1. Fixed on opposite ends of the shaft 73 are arms 75 having rollers 76 on the 60 extremities thereof, the rollers 76 being positioned

to contact the levers 34 of each of the plates 30. Pivotedly mounted on the right hand post 18 is a manually operable lever 78 which is connected to the arm 75 therebelow by a link 79.

The nailing mechanism 14 includes a pair of 5 identical nailing units 85, each of these including a beam 86 slidable vertically on bars 87 mounted on the plates 20 and 21, the beams 86 having nail chucks (not shown) provided thereon. Fixed on the beams 86 are brackets 89 in which end tuckers 90 are pivotedly mounted, the latter serving to support a lid L as shown in Fig. 1. Supported by the plates 20 and 21 between the nailing units 85 is a strapper unit S, the latter being disclosed in the above referred to copending application. Carried by the beams 86 and the strapper S is a crown sheet 92.

Operation

When a standard box, such as the box B shown 20 in Figs. 1, 2 and 3, is to be lidded by the machine 10, the lever 78 is positioned as shown in Fig. 2, allowing the levers 34 and 35 to engage the under side of the flusher shafts 47. After the box B rolls onto the table 13 and is positioned thereon by the stops 42 and 43, the power unit 12 is energized by the operator causing the table 13 to be 25 lifted as shown in Fig. 3. The flusher shafts 47 are retained in the upper ends of the slots 32 by the levers 34 and 35 and the flushers 45 and 46 30 are swung inward by contact of the cams 52 with the rollers 49 of the levers 48. As the flushers 45 and 46 swing inward, the flusher bars 56 contact the overfilled portion of fruit F in the box B and move the fruit at the sides of the box inward 35 from over the upper edges of the sides of the box as shown in Fig. 3. Continued upward movement of the box B brings the upper edges of the ends thereof into contact with the end tuckers 90 which serve to move the fruit at the ends of the 40 box inward from over the upper edges of the box ends. The lid L is then pressed onto the fruit F by the crown sheet 92 and the ends of the lid nailed to the box ends by the nailing units 85.

When a half box B', as shown in Fig. 4, is fed 45 to the machine 10, the operator pulls the lever 78 down causing the shaft 73 to rotate, the arms 75 thereof being raised. As the arms 75 swing upward, the rollers 76 thereon force the levers 34 and 35 out from under the ends of the flusher shafts 47, the latter being retained in the upper 50 ends of the slots 32 by engagement of the blocks 50 with the rollers 49 of the levers 48. When the table 13 is raised to fix a lid on the box B', the side flushers 45 and 46 remain stationary until 55 the ends of the flusher shafts 47 are engaged by the lower ends of the slots 32. The flushers 45 and 46 then function as shown in Fig. 5 in substantially the same manner described relative to the lidding of the standard box B.

When the table 13 is lowered after the box B' is lidded, the blocks 50 again engage the rollers 49 of the levers 48 and retain the flushers 45 and 46 while the table 13 continues downward to the 60 position in which it is shown in Fig. 4.

It is thus seen that by raising or lowering the lever 78, the flushers 45 and 46 can be properly positioned to operate on either a standard or a 65 half box.

Referring now to Fig. 7, we have shown therein 70 the operation of the stops 60 during the lidding of the standard box B as compared with the operation thereof during the lidding of an export box E, shown in Fig. 8. When positioned as shown in Fig. 7, the stops 60 contact the sides 75

95 of the box B, thus limiting the inward movement of the flushers 45 and 46 so that the innermost faces of the bars 56 thereof are disposed in vertical alignment with the inside surfaces of 5 the sides 97 of the box.

When the export box E is to be lidded, the operator pulls down on the lever 62 causing all four of the stops to be raised into inoperative position as shown in Fig. 8, thus allowing the inner faces 10 of the flusher bars 56 to move into vertical alignment with the inner surfaces of the thick sides 96 of the box E while the vertical bars 55 of the flushers 45 and 46 contact the outer surfaces of the sides 96. The lever 62 is retained in either its 15 upper or lower position by the overthrow spring 64.

It is thus seen that the stops 60 included in the machine 10 of our invention enable the flushers 45 and 46 to operate correctly on either domestic 20 boxes or export boxes having extra thick side walls.

Although we have shown and described but one preferred form of machine of our invention, it is to be understood that various modifications and 25 changes might be made therein without departing from the spirit of the invention or the scope of the appended claims.

We claim as our invention:

1. In a lid pressing machine, the combination 30 of: a frame; a box supporting table on said frame; lid pressing means on said frame above said table; power means causing relative vertical movement between said pressing means and said table; flushing means on said table for engaging fruit overlying upper edges of said box to move said fruit inward from over said edges; and control means for selectively rendering said flushing means effective at different vertical positions relative to said table, to cause said flushing means 35 to function on boxes of different heights.

2. A combination as in claim 1, in which at least one vertical relation as aforesaid between said table and said flushing means, after having been preselected by actuation of said control 40 means, is effected by relative vertical movement between said flushing means and said table incidental to the relative vertical movement aforesaid between said pressing means and said table.

3. In a cover pressing machine, the combination 45 of: a frame; a box supporting table movable vertically on said frame; power means for elevating and lowering said table; cover pressing means on said frame above said table; flusher means on said table for engaging fruit overlying upper edges of said box and moving said fruit inward from over said edges to prevent injury to said fruit by said edges during a pressing operation; and control means for selectively rendering said flusher means effective at different vertical positions relative to said table, to cause said flusher means to engage the crown portion of the pack of boxes of different heights.

4. In a machine for applying a lid to an overfilled box of fruit, the combination of: a frame; a box supporting table on said frame; lid applying means on said frame over said table; power means causing relative vertical movement between said lid applying means and said table; flushing means pivotally mounted at each side 50 of said table for engaging fruit overlying upper edges of the sides of said box to move said overlying fruit inward from over said edges; and control means for selectively rendering said flushing means effective at different vertical positions relative to said table, to cause said flushing means

to engage the overfilled portion of the pack of boxes of different heights.

5. In a machine for applying a lid to an overfilled box of fruit, the combination of: a frame; a box supporting table on said frame; lid applying 5 means on said frame over said table; said table and lid applying means being capable of being spaced apart maximum and minimum distances; power means causing relative vertical movement between said lid applying means and said table 10 to change from maximum to minimum spacing and vice versa; a rotatable shaft at each side of said table, said shafts being parallel with the longitudinal axis of said table and movable vertically relative to said table; side flushers carried 15 by said shafts for engaging fruit overlying upper edges of the sides of said box to move said fruit inward from over said edges; means for causing said shafts to be located at given vertical positions relative to said table when said 20 table and said lid applying means are at maximum spacing as aforesaid; and means for causing said shafts to be located at any one of a plurality of vertical positions relative to said table when said lid applying means and said table approach minimum spacing as aforesaid to permit 25 said flushers to engage the fruit overlying the upper edges of the sides of any one of a plurality of boxes of different heights.

6. In a machine for lidding an overfilled box 30 of fresh fruit, the combination of: a frame; a box supporting table on said frame; lid securing means on said frame over said table; flushing means for engaging fruit overlying upper edges of the sides of said box to move said fruit inward 35 from over said edges to prevent injury to said fruit during the lidding of said box by said lid securing means; stop means on said flushers, the innermost position of said flushers relative to said box sides being determined by contact of said 40 stop means with the outer surfaces of the sides of said box; and means operable from a single station for adjusting said stop means to vary the position of said flushers relative to the outer surfaces of the sides of a box to permit said flushers 45 to operate on boxes having sides of different thicknesses.

7. In combination: a table for supporting an over-filled box; a presser head disposed above said table; means for causing relative movement 50 between said presser head and said table to apply pressure to the over-pack in said box to arch the same preparatory to lidding said box; a gathering member; means for shifting said gathering member inwardly toward said box prior to the 55 consummation of said pressing movement to shift edge portions of said over-pack inwardly from over a vertical wall of said box to prevent pinching of said edge portions incidental to said pressing operation; means for supporting said member on said table either in a position to operate properly on a box of one standard height or in a position to operate properly on a box of a substantially different standard height when 60 shifted inwardly as aforesaid; and gathering member support control means adapted to be actuated prior to the beginning of a given relative vertical movement as aforesaid to selectively determine in which of said positions, said support 65 means will support said member during a cover pressing operation to take place during said particular relative vertical movement, any change in vertical relation between said member and said table necessary to carry out the selection 70 75

made by said control means being effected automatically by said relative vertical movement.

8. In combination: a table for supporting an over-filled box; a presser head disposed above said table; means for causing relative movement between said presser head and said table to apply pressure to the over-pack in said box to arch the same preparatory to lidding said box; a flusher bar disposed along one side of said box when it is positioned on said table; means for moving said bar inwardly prior to the consummation of said pressing movement to shift edge portions of said over-pack inwardly from over a side of said box; means for supporting said flusher bar on said table either in a position to operate properly on a box of one standard height or in a position to operate properly on a box of a substan-

tially different standard height when shifted inwardly as aforesaid; and flusher bar support control means adapted to be actuated prior to the beginning of a given relative vertical movement as aforesaid to selectively determine in which of said positions, said support means will support said flusher bar during a cover pressing operation to take place during said particular relative vertical movement, any change in vertical relation between said flusher bar and said table necessary to carry out the selection made by said control means being effected automatically by said relative vertical movement.
